LLP

(73) Assignee: **Trimble Navigation Limited,
Sunnyvale, CA (US)**

(57) **CLAIM**

The ornamental design for a position determining system and radio receiver, as shown.

(**) Term: **14 Years**

DESCRIPTION

(21) Appl. No.: **29/121,197**
(22) Filed: **Mar. 30, 2000**
(51) LOC (7) Cl. **10-04**
(52) U.S. Cl. **D10/65; D10/78**
(58) Field of Search D10/65, 78; 73/128;
340/995; 342/98, 102, 113, 115, 352, 356,
357, 359, 417-421; 364/200, 434, 443,
444, 449, 451, 708.1, 709.11

(56) **References Cited**

FIG. 1 is an upper right front perspective view, of the position determining system and radio receiver comprising the present invention;

FIG. 2 is a lower left rear perspective view thereof;

FIG. 3 is a front elevational view thereof;

FIG. 4 is a right side elevational view, with the left side elevational view being a mirror image thereof;

FIG. 5 is a rear elevational view thereof;

FIG. 6 is a top plan view thereof; and,

FIG. 7 is a bottom plan view thereof.
